UNITED STATES PATENT OFFICE.

CHARLES H. BUCK, JR., OF ST. LOUIS, MISSOURI.

DESIGN FOR A STOVE.

SPECIFICATION forming part of Design No. 13,540, dated January 23, 1883.

Application filed July 14, 1882. Term of patent 3½ years.

To all whom it may concern:

Be it known that I, CHARLES H. BUCK, Jr., a citizen of the United States, residing at St. Louis, Missouri, have invented and produced 5 a new and original Design for Stoves, of which the following is a specification, reference being had to the accompanying drawing, forming part thereof.

The drawing shows the newly-designed stove 10 in perspective.

The present invention is an improvement in what are known to the trade as "cannon stoves."

In the present construction the bottom cylinder, A, is truly conoidal, the shell *a* being neither convex nor concave. The top cylinder, B, which rests upon and is fitted to the bottom cylinder, is semi-spheroidal in elevation, the shell *b* being convex as high as the 15 neck *b'*, at which level the shell curves outward to unite with the top C, as shown. The bottom cylinder, A, rests upon the base D, which is of the usual description, saving that

the door *d* and door-frame *d'* are concave in elevation, as shown. Between the cylinders A 25 and B, and at a point about midway between base D and top C, is the horizontal and projecting flange *e*. The coal-supply door in the part B is above and independent of the flange *e*.

I claim—

1. The design for a cannon stove, consisting of the conoidal lower cylinder, A, the semi-spheroidal top cylinder, B, the top C, the base D and door *d*, and frame *d'*, substantially as described.

2. The design for a cannon stove herein shown and described, consisting of the conoidal lower cylinder, A, the semi-spheroidal top cylinder, B, the central flange, *e*, between the two, the door in cylinder B above and independent of the flange *e*, the top C, and base D, having door *d*.

CHARLES H. BUCK, JR.
